FERRULE REFORMING APPARATUS

Jesse B. Goodgame, Charlotte, N. C., and Connie Dexter Baker, Sr., Lancaster, S. C., assignors to Precision Gear and Machine Company, Charlotte, N. C., a corporation of North Carolina

Application November 18, 1949, Serial No. 128,194

6 Claims. (Cl. 153—48)

1

This invention relates to a press for forming objects and more especially to a press for straightening and rendering circular ferrules which are placed on the ends of paper bobbins or tubes when they shall have become out of round by being run over by a truck or stepped on.

It is well known that in the textile industry tubes and bobbins are made of paper and have metallic ferrules at each end thereof. In one type of bobbin or tube the upper end of the bobbin which sits on a spindle has a ferrule which is restricted and frictionally engages the spindle on which the same is placed and therefore must be perfectly round in order to fit onto the spindle. These bobbins after being processed very often fall onto the floor and are stepped on or the wheel of a truck passes over the same which results in their being crushed to an out of round position. It is an object of this invention to provide a suitable press into which the tubes can be placed for rendering the ferrules, preferably on the base of the bobbin, perfectly circular for further use.

In bobbins of this nature, the ferrule on the lower end of the bobbin fits tightly against the exterior and interior surfaces of the base of the bobbin and does not have the rigidity of the ferrule at the top or tip end of the bobbin which extends inwardly from the inner walls of the tube or bobbin and therefore lends rigidity to the ferrule so that it is not easily crushed, but the ferrule around the base of the bobbin by fitting tightly around the inner and outer surfaces of the bobbin does not have the required metal stock therein to withstand pressure and when the wheels of a truck or the foot of an operator engages the same the bobbin is very often mashed to an out of round position and this must be brought back to a true circular position before it can be further used.

Some of the objects of the invention having been stated, other objects will appear as the description proceeds, when taken in connection with the accompanying drawings, in which—

Figure 1 is a top plan view of the apparatus omitting pipes for carrying compressed air;

Figure 2 is a longitudinal vertical sectional view taken substantially along the line 2—2 in Fig. 1;

Figure 3 is a sectional view through the control valve showing the core in one position;

Figure 4 is a sectional view through the control valve and showing the core in another position;

Figure 5 is a longitudinal sectional view similar to Figure 2 but showing a modification of the invention;

2

Figure 6 is an enlarged longitudinal sectional view taken along the line 6—6 in Figure 1 with the middle portion thereof broken away.

Referring more specifically to the drawings the numeral 10 indicates a suitable support such as a table for supporting the apparatus. A base member 11 is suitably secured by means shown in Figures 1 and 2 to the support 10 which base member 11 has adjustably mounted thereon a dovetailed member 12 which is secured in position by means of bolts 13. The member 12 has a bore 14 therein in which is adjustably mounted a pilot member 15 having a projection 16 forming a circular groove 17 and which acts as a pilot for one end of the tube to be presently described. The pilot member 15 is secured in position in the member 12 by means of a set screw 18.

The base member 11 has integral therewith a barrel portion 20 having a bore 21 therein in which is slidably mounted a tubular member 22 which has a bore 23 extending longitudinally thereof and this bore 23 is flared outwardly as at 24 at its right hand end in Figure 2. The open end of the bore 21 is closed by an annular plate 25 secured in position by any suitable means such as screws 26. Between the slideable die member 22 and a restricted portion 27 of the bore 21 is a compression spring 28. The barrel member 20 also has a bore 30 of slightly smaller diameter than the bore 21 and which communicates with the restricted portion 27. The restricted portion 27 has a bearing ring 33 therein and slidably mounted in the bearing ring 33 is an enlarged portion 35 of a plunger 36 which has a tapered portion 37 adapted to enter the end of the tube T.

The tube T has a ferrule 40 around its base portion (Figure 2) and another ferrule 41 around its tip portion. The ferrule 41 extends inwardly a substantial distance from the inner surface 49 of the tube T and turns inwardly to provide a restricted bore B for fitting around the tip portion of a spindle.

The die member 22 is restricted at its outer end where it passes through the annular plate 25 thus providing a shoulder 46 for limiting outward movement of the member 22 under pressure of the compression spring 28. The bore 30 is open at its right-hand end and the barrel portion 20 is provided with a flange 45 to which is secured by bolts 47 a flanged portion 48 of an annular member which is threaded to receive one end of a cylinder 50 in which is mounted a piston 51 penetrated by a piston rod 52 which is integral with the portion 35. The piston rod 51 is slidably mounted in a bearing ring 49 mounted in

the annular member 48. The piston 51 is secured on the piston rod 52 by any suitable means such as the right-hand end of the rod 52 being threaded and receiving a nut 54.

At the right-hand end of the cylinder 50 is a closure plate 60 which has an annular rib 61 threaded interiorly for receiving the right-hand end of the cylinder 50. The closure plate 60 has suitable holes 62 therethrough for securing the same to the support 10. The closure plate 60 has a bore 64 through which communicates with a bore 65 in a closure plate 66 secured to the plate 60 by any suitable means such as bolts 67. The member 48 has a bore 70 therethrough which communicates with the left-hand end of the cylinder 50 and secured in this bore is a pipe 71 which leads to one of the ports of a valve housing 72 having a core 73 therein provided with passageways 74 and 75. The valve core 73 is fixed on a shaft 76 which extends to the outside of the valve housing 72 and has an operating handle 77 fixed thereon. The valve housing 72 also has a second port to which a pipe 80 is secured and this pipe 80 extends to and is threadably secured in bore 65 of plate 66. The valve housing 72 also has a pipe 82 leading from a third port which pipe 82 is a supply pipe and leads to a suitable source of compressed air such as a tank 85. The valve housing 72 also has an exhaust port 86 through which air is exhausted in the operation of the machine.

In operation tube T is inserted into the flared out cavity 24 and pressure is applied toward the right in Figures 1 and 2 which will compress the compression spring 28 and allow the tip end of the tube to be fitted over the projection 16 and rest in position shown best in Figure 6. The pressure of spring 28 will hold it in this position and then the valve port 73 will be turned to the position shown in Figure 3 which will allow compressed air to pass through passageway 75 and pipe 80 to the right-hand end of the cylinder 50 which force the piston 51 to the left in Figure 2 and which will deliver an impact to the tapered portion 37 to cause it to fit into the right-hand end of the tube T or the position shown in Figure 6 which will restore the right-hand end of the tube T to circular position.

Then the valve core 73 is switched to the position shown in Figure 4 which will allow the air to exhaust from the right-hand end of the cylinder 50 through the passageway 75 and exhaust port 86 and at the same time will allow compressed air to flow through passageway 74 into the left-hand end of cylinder 50 which will withdraw the piston and the tapered portion 37 of the plunger to the right as shown in Figure 2 but, of course, continued pressure will force the right-hand end of the piston rod 52 to the right-hand end of the cylinder and against the plate 60.

In this position the tube T may be withdrawn from the apparatus and a new tube inserted.

In Figure 5 a slightly modified form of the invention is shown and the left-hand end of the invention being identical to that shown in Figures 1 and 2 will bear the same reference characters. The structure shown in Figure 5 is operated by hand or foot power or manually instead of by compressed air or other compressed fluid as shown in Figures 1 and 2. In this form of the invention, the base plate 11 is shown as being secured to a suitable support 10 by bolts 100. The base plate 11 has a slightly modified portion 101 integral therewith differing from the portion 20 in the previously described form of the inven-

tion. This portion 101 has a bore 102 of the same size as the bore 21 in which the member 22 is mounted and a compression spring 28 identical to that shown in Figure 2 is disposed around the enlarged portion 35 and extending from this portion 35 is a piston 104 which has a piston 105 thereon. The enlarged portion 35 extends through a bearing 107 before it is reduced in diameter to form the piston rod 104. The compression spring 28 serves the same purpose, that is to move the annular die member 22 toward the left in both Figures 2 and 5. The piston 105 instead of being propelled by air pressure is propelled by a compression spring 108 which is disposed in a bore 109 which bore also accommodates the piston rod 104. The right-hand end of the portion 101 is flared as at 111 and a closure plate 112 is secured thereon by any suitable means such as bolts 113.

The base portion 11 in the modified form has a downwardly projecting ear 115 extending through an opening 116 in the support 10 and has pivoted thereto on a pivot 114 a bell crank C having a lower arm 117 and an upper arm 118. On the upper arm 118 is pivoted as at 119 a dog 120 which is held against a projection 121 extending from the arm 118 by means of a tension spring 123 secured to the upper portion of the dog at one end and to the outer end of the arm 117 as at 124.

Pivoted to the outer end of the arm 117, as at 126, is a link 127 which extends downwardly and is pivoted as at 130 to a foot lever 131 which foot lever is normally held in solid line position by means of a tension spring 132. This foot lever 131 is pivoted as at 133 on a stand 134 rising from a suitable support such as a floor 135 of a building. The left-hand end of the foot lever 131 has a pedal portion 136 so that an operator can step upon the pedal 136 to move the bell crank C in a clockwise manner in Figure 5 which will compress the compression spring 108 and retract the tapered portion 37 from the solid line position shown in Figure 5 to the dotted line position or until the upper end of the dog 120 passes by the piston 105 which will cause the spring then suddenly to force the piston 105 and associated parts quickly to the left in Figure 5 which will drive the tapered portion 37 into the nearest end of the tube T or to the solid line position shown in Figures 5 and 6 to thus deliver an impact to straighten out and render circular the ferrule 40 on the base of the tube T.

In the drawings and specification there has been set forth a preferred embodiment of the invention, and although specific terms are employed, they are used in a generic and descriptive sense only, and not for purposes of limitation, the scope of the invention being defined in the claims.

We claim:

1. Apparatus for reforming deformed ferrules on the ends of a tubular bobbin comprising a fixed pilot member for receiving one end of the tube, a resiliently mounted tubular member having an outwardly flared circular cavity in the end thereof disposed next to the pilot member and urged toward the fixed pilot member for receiving the other end of the tube, a reciprocable plunger having a tapered end and mounted for sliding movement in the resiliently mounted tubular member, means for moving the plunger away from the adjacent end of the bobbin and means for moving the plunger toward the bobbin to cause its tapered end to fit in the bobbin to re-

form the ferrule on the end thereof into substantially circular shape.

2. Apparatus for reforming off round ferrules on one end of a tubular bobbin comprising a pilot member for supporting one end of the bobbin and a resiliently mounted tubular member urged towards the pilot member and into which the other end of the bobbin is adapted to fit, a plunger slidably mounted in the resiliently mounted tubular member and having a tapered end for fitting into the end of the bobbin, means for moving the resiliently mounted tubular member into engagement with the exterior of that end of the bobbin having the ferrule thereon, means for forcing the tapered end of the plunger into the end of the bobbin having the ferrule thereon to restore its circular condition and means for withdrawing the tapered end of the plunger from the bobbin and telescoping it into the resiliently mounted tubular member to permit the insertion of a new bobbin.

3. Apparatus for reforming out-of-round metal ferrules disposed on one end of a tube, comprising a pilot member for supporting one end of the tube and a tubular member for receiving the other end of the tube and supporting the same, a plunger slidably mounted into the tubular member and having a tapered end adapted to project from the tubular member, means resiliently pressing the tubular member into engagement with the exterior of the end of the tube having a ferrule thereon, means for forcing the tapered end of the plunger into that end of the tube encircled by the ferrule to restore the ferrule thereon to a circular condition and means for withdrawing the tapered end of the plunger from inside the tube to allow the removal of the tube and the placing of a new tube in position on the pilot member and within the tubular member.

4. Apparatus for reforming metallic ferrules on a tubular bobbin comprising a pilot member for supporting one end of the bobbin and a tubular member mounted for sliding movement towards and away from the pilot member for receiving the other end of the bobbin, the other end of the bobbin having a metallic ferrule thereon, the tubular member having an outwardly beveled interior surface to cause it to receive and fit against the exterior surface of the ferrule on the bobbin, a plunger slidably mounted in the tubular member and having a tapered end for entering the end of the bobbin having the ferrule thereon for restoring it to a circular condition, fluid pressure means for moving the plunger into the end of the bobbin having the ferrule thereon to restore the ferrule to a circular condition, means controlling the fluid pressure means to cause the plunger to enter the end of the bobbin to restore the ferrule thereon to a circular condition and means for

controlling the fluid pressure means to withdraw the tapered end of the plunger from the end of the bobbin having the metallic ferrule thereon.

5. Apparatus for reforming metallic ferrules on a tubular member, such as a tubular paper bobbin, comprising means for supporting one end of the bobbin, a tubular member having an enlarged interior beveled end for receiving that end of the bobbin having the ferrule thereon and being mounted for sliding movement towards and away from the bobbin, resilient means for moving the tubular member to cause it to encircle the end of the bobbin having the ferrules thereon, a plunger slidably mounted in said tubular member and having a tapered end, means for moving the plunger into that end of the bobbin having the ferrule thereon for restoring the ferrule to a circular position and means for withdrawing the tapered end of the plunger from within the bobbin to allow removal of the same from the pilot member and from within the tubular member.

6. Apparatus for restoring a metallic ferrule on a tubular bobbin to a circular condition comprising a pilot member for supporting one end of the bobbin and a tubular member having a beveled interior surface for receiving the other end of the bobbin having a metallic ferrule thereon and being mounted for sliding movement towards and away from the bobbin, resilient means for moving the tubular member over the end of the bobbins having a metallic ferrule thereon, a plunger slidably mounted in said tubular member and having a tapered end for entering the end of the bobbin having the metallic ferrule thereon for restoring the ferrule to a circular condition, resilient means for moving the plunger into the end of the bobbin having the ferrule thereon and means for withdrawing the plunger from the interior of the bobbin and allowing escapement of the plunger by the means for moving the same out of the end of the bobbin to allow the resilient means to quickly move the plunger into the end of the bobbin to impart a stroke thereto to restore the ferrule on the end of the bobbin and encircled by the tubular member to a circular condition.
